(57) **CLAIM**

The ornamental design for a sock package, as shown and described.

DESCRIPTION

FIG. 1 is a top front perspective view of the sock package embodying my design;

FIG. 2 is a front elevation of the sock package of FIG. 1, showing the socks (which do not form part of the design) in dotted outline;

FIG. 3 is a top plan view of the sock package of FIG. 1; FIG. 4 is a right side elevation of the sock package of FIG. 1;

FIG. 5 is a left side elevation of the sock package of FIG. 1; and,

FIG. 6 is a bottom plan view of the sock package of FIG. 1.
